UNITED STATES PATENT OFFICE.

THOMAS Z. MERRITT, OF OMAHA, NEBRASKA, ASSIGNOR OF FORTY-NINE ONE-HUNDREDTHS TO JOHN E. WAKEFIELD, OF OMAHA, NEBRASKA.

FLOOR OR WALL SCREED.

1,171,452.

Specification of Letters Patent. Patented Feb. 15, 1916.

Application filed April 28, 1915. Serial No. 24,570.

REISSUED

To all whom it may concern:

Be it known that I, THOMAS Z. MERRITT, a citizen of the United States, residing at Omaha, in the county of Douglas and State 5 of Nebraska, have invented certain new and useful Improvements in Floor or Wall Screeds, of which the following is a specification.

This invention relates to an improvement 10 in a floor or wall screed, and has for its object, broadly, to provide screeds which will consist of few and simple parts so that manufacture will be convenient and economical, and which may be readily applied 15 to the walls, partitions or floors of buildings without the use of nails or screws, for use as supports for wood or metallic casings, wall-strips or other like parts employed in finishing the interior of buildings.

20 The invention consists of the novel construction, combination and arrangement of parts as described herein and claimed, and as illustrated in the drawing, it being understood that changes in form, size, proportion 25 and material may be made within the scope of the claim without departing from the spirit of the invention or sacrificing any of its advantages.

In the accompanying drawing which 30 forms a part of the application, Figure 1 is a broken away view showing a part of an upright wall or partition of a building with the screeds mounted therein. Fig. 2 is a plan view showing a part of a wall or 35 partition with the screeds mounted therein, the view being in transverse section, a portion of a wall-strip being added. Fig. 3 is a diagrammatic view showing a metallic sheet or plate used as a holder for the block 40 or pillow. Fig. 4 is a front view showing the block or pillow mounted upon the plate. Fig. 5 is a transverse section on line 5 5 of Fig. 4. Fig. 6 is a view showing the screed applied to a building wall or partition, as a support for a wall-strip or casing, said strip or casing, the plaster and 45 wall or partition being in section.

Referring now to the drawing for a more 50 particular description, numeral 7 indicates a block or pillow which may be constructed of wood, metal or any other suitable material adapted to operate as a support and as a retainer for nails or screws. It is preferably of rectangular form, of uniform 55 thickness, and each of its sides is inclined

inwardly from the back to the front, and thereby providing the inclined facets *a*.

Numeral 8 indicates a rectangular metallic plate which may be incised on parallel lines *b* *c* and lines *c* *c*, the parts between 60 said lines being bent outwardly on lines *b* *b*, inwardly of two opposed edges, to form recesses *d* (Fig. 5) and to form the flanges or clasps 9, their inclination with reference to the plate corresponding to the shape or 65 inclination of the facets *a* of the block 7, and the plate is provided, near its edges with apertures 10, the remaining part of the plate or that part between the flanges and recesses *d* preferably being imperforate. 70 The block is disposed on the imperforate part of the plate above recesses *d* with two of its inclined sides embraced by the flanges or clasps 9 which operate to maintain the block between the rows of apertures 10. 75

In operation, the screed is attached to the wall 11 by use of plaster of Paris 12 or other adhesive material by pressing the plate 8 against the wall, the plastic adhesive being compressed between the wall 80 and said plate so that it will, in part, move forwardly through apertures 10. If plaster of Paris is used it will soon become dry and firm and the device will be securely held to the wall. 85

The screeds may be disposed in alinement as shown in Figs. 1 and 2, their thickness being substantially equal to the plaster 13 which is then applied to the wall. Since the area in plan of the plate is greater than 90 that of the block, the plaster will cover a considerable part of the plate, and will also cover the inclined sides of the blocks so that they will be firmly held by the plaster. As shown in Figs. 2 and 6, a rail, wall-strip 95 or casing 14 may be secured to the screeds by keepers 15, and the screeds provide an adequate support therefor.

Among some of the advantages to be derived by use of the screeds it may be stated 100 that, where brick, stone, tile or cement are used for the walls or partitions, the conventional channels or recesses usually provided therein for containing anchor-blocks or strips may be dispensed with, which results in a saving of time and labor. Also the parts employed in constructing the screeds are few, and they may be manufactured conveniently at, comparatively, a limited cost. 105 110

Having fully described the construction and function of the parts, a further explanation relating to operation is not necessary.

What I claim and desire to secure by

5 Letters Patent, is,—

In concrete or similar floor or wall construction, the combination with a support, adhesive portions disposed at spaced intervals in horizontal alinement on the support, a plurality of plates having the entire areas of their inner sides formed rectilinear and mounted on said adhesive portions, each being provided on its outer side with a pair of transversely inclined flanges 10 25 extending parallel in one direction, said

plates being formed outwardly of said flanges with apertures to permit a passage therethrough of a part of said adhesive portions, a plurality of fiber-blocks each being disposed upon a plate between the flanges 20 thereof, and a layer of plastic material surrounding said blocks and leaving a part of each block exposed.

In testimony whereof, I have affixed my signature in presence of two witnesses.

THOMAS Z. MERRITT.
